[57] **ABSTRACT**

Control apparatus for effecting a plurality of output functions, comprising a drive member that is movable into driving engagement with each of a plurality of driven output members, a movable input member having a cam groove disposed on the outer surface thereof, and a pin mounted on the drive member and slidably engaged in the cam groove. Depending on the configuration of the cam groove, the movement of the input member may cause the pin to move along the cam groove and to effect movement of the drive member into driving engagement with one of the output members, or may cause the pin to move with the input member to thus effect movement of the drive member with the input member.

CONTROL APPARATUS

BACKGROUND OF THE INVENTION

This invention relates to apparatus for controlling the positioning and driving movement of a drive member that is sequentially movable into driving engagement with a plurality of output members for effecting a plurality of output functions. More particularly, the invention relates to such an apparatus wherein the positioning and driving movement of the drive member are controlled by a movable input or cam shaft having a cam groove therein.

Heretofore, in apparatus that has been utilized for effecting a plurality of output functions by controlling the movement of a drive member sequentially into driving engagement with one or more output members, complicated linkage and or multiple driving arrangements have been required to control the position and driving movement of the drive member. In many instances, a plurality of complex linkage arrangements have been utilized, each one being controlled by separate drive means, such as a plurality of electric motors. These prior art control assemblies have been subject to numerous disadvantages; namely, they have been complicated in construction, expensive to manufacture, relatively heavy and/or bulky, and have been of relatively low reliability owing to their complicated construction and their need for a plurality of drive means, such as multiple electric motors, which has increased the chances of a malfunction.

The previously utilized control assemblies have been particularly unsuitable in space applications where low weight, minimum complexity and high reliability are required for all systems utilized in space vehicles. A particular need has arisen in the space field for a highly reliable, lightweight and simple control assembly to be used, for example, for positioning a payload at any point in one, two or three dimensional space. The previously and presently utilized control assemblies have failed to satisfactorily fulfill this need.

SUMMARY OF THE INVENTION

The control apparatus of the present invention is very simple in construction, lightweight and highly reliable in operation, and can be utilized for effecting a plurality of output functions, such as the positioning of a payload at any point in one, two or three dimensional space. Also, the control apparatus of this invention is readily adaptable to automated assembly line machinery for effecting a plurality of sequential output functions. In the present control apparatus, a sequence of any number of output functions may be obtained through the use of a single bi-function input such as a reversible electric motor.

The control apparatus of the present invention comprises an input shaft that is rotatable in opposite directions by a reversible drive means, such as an electric motor. An axially and circumferentially extending cam groove of any desired configuration is disposed on the outer surface of the input shaft. A drive member is mounted on the input shaft for rotatable and axial movement relative thereto, and a pin mounted on the drive member is positioned within the cam groove for sliding movement therein. In addition, a drag device is engaged with the drive member causing translation owing to input shaft rotation and allowing rotation

when the pin mounted in the drive member reaches a drive point in the cam groove. Rotation of the input shaft, therefore, results in rotation and/or axial movement of the drive member, owing to the rotation of the pin with the cam shaft or the translating movement of the pin in the cam groove.

A plurality of output members are mounted adjacent the drive member for driving engagement therewith. By rotating the input shaft in a predetermined manner, the drive member may be moved into sequential driving engagement with each of the output members so as to effect a plurality of output functions, depending on the output member with which the drive member is drivingly engaged, and the direction of rotation of the drive member. In order to increase the number of output functions that may be effected by the single rotatable input shaft, a plurality of cam grooves of the same or different configuration may be provided on the exterior surface of the input shaft, and a plurality of drive members may be mounted on the input shaft for cooperation with each of the cam grooves. Each of the drive members, therefore, would be drivingly engageable with different output members for effecting numerous output functions.

The drive and output members may be in the form of gear members or any other type of drive transfer members. Alternatively, the drive member may be a follower member that is movable, owing to rotation of the input shaft and the friction of the drag device, into driving engagement with an output member such as a drive transfer wheel of the like which is, in turn, drivingly engageable with other output means. The cam groove or grooves may be formed in the outer surface of the input shaft or may be formed in the outer surface of one or more annular cam members mounted on the input shaft for rotation therewith.

BRIEF DESCRIPTION OF THE DRAWINGS

FIG. 1 is a perspective view, with parts shown in section and parts broken away, of a control apparatus constructed in accordance with the principles of the present invention;

FIG. 2 is a side elevational view, with parts broken away, of the cam groove on the input shaft of the apparatus shown in FIG. 1;

FIG. 3 is an enlarged fragmentary perspective view of a portion of the present control apparatus, showing a section of the cam groove on the input shaft and the drive member or follower pin slidably disposed therein;

FIG. 4 is a side elevational view similar to FIG. 2 showing a modified cam groove on the input shaft;

FIG. 5 is a side elevational view, with parts shown in section and parts broken away, of a modified form of control apparatus constructed in accordance with the principles of the present invention;

FIG. 6 is an elevational view, with parts broken away and parts shown in section, of a portion of the apparatus shown in FIG. 5, and

FIG. 7 is a side elevational view, with parts broken away, of a portion of the apparatus shown in FIG. 5.

DESCRIPTION OF THE PREFERRED EMBODIMENTS

As shown in FIG. 1, the control apparatus 10 of the present invention comprises a rotatable input shaft 12

that is adapted to be driven by any suitable type of reversible drive means such as a reversible electric motor (not shown). Mounted on and secured to the input shaft 12 is a cam shaft 14 having an axially and circumferentially extending cam groove 16 formed in the exterior surface thereof. Within the scope of the present invention, the cam groove 16 may be of any desired configuration, and may be formed directly in the exterior surface of the input shaft 12 rather than on the exterior surface of a separate cam shaft or member 14.

A drive member of any suitable type, such as an annular gear member 18 is rotatably and slidably mounted on the cam shaft 14, or on the input shaft 12 in the case where the cam groove 16 is formed directly in the exterior surface of the input shaft, such that the drive gear member 18 is rotatably and axially movable relative to the cam shaft 14 and the input shaft 12. As shown in FIGS. 1 and 3, the exterior surface of the gear member 18 is provided with a recess or bore 20 in which a pin 22 is slidably mounted. The inner end of the pin 22 is slidably disposed in the cam groove 16 and is urged into engagement with the cam groove by a spring 24 of any suitable type disposed within the bore 20 of the gear member 18.

Any suitable drag device 17 may be utilized to provide friction forces to cause pin 22 to translate in the cam groove 16 when position change is commanded by the input shaft 12. For example, a drag device such as the gear 17 may be spring loaded into continuous engagement with the gear member 18 throughout its entire path of movement so as to supply the required drag force. Further, when the pin 22 reaches a drive position 16a in the cam groove 16, the friction force supplied by the drag gear 17 is overcome allowing rotation of the drive gear 18 with input shaft 12.

A plurality of output members of any suitable type, such as gear members 26, are mounted for independent rotation on a shaft 28 and are positioned so as to be drivingly engaged by the gear member 18 in a manner to be described hereinafter. Alternatively, the output gear members 26 could be mounted on separate shafts, or if face gears were used on the same input shaft 12 or cam shaft 16. The gear members 26 may be operatively connected to different drive transfer or gearing arrangements (not shown) depending on the particular output functions desired as a result of the rotation of each of the gear members 26. As an illustrative example, each of the output gear members 26 could effect different types of positioning movements in any suitable type of output device (not shown).

In the operation of the control apparatus 10, it will be readily seen that rotation of the input shaft 12 and the cam shaft 14 can effect rotation of the drive gear member 18 therewith or axial movement of the gear member 18 along the cam shaft 14, owing to the friction of the drag device 17 and the position or movement of the pin 22 in the cam groove 16. The sequence of movements of the drive gear member 18 relative to the cam shaft 14 is determined by the configuration of the cam groove 16, and this would ultimately depend on the type and the sequence of output functions to be effected by rotation of the output gear members 26. By rotating the input shaft 12 in a predetermined direction, the drive gear member 18 can be sequen-

tially translated in an axial direction along the cam shaft 14 such that it is sequentially brought into driving engagement with each of the output gear members 26 so as to rotatably drive them in a timed sequence that is determined by the configuration of the cam groove 16 and the speed and direction of rotation of the input shaft 12.

As an illustrative example, FIGS. 1 and 2 disclose one type of cam groove 16 that may be utilized with the present apparatus, when it is desired to sequentially rotate the output gear members 26 in opposite directions. The cam groove 16 is provided with alternating axially and circumferentially spaced stop positions 16a which are disposed such that the drive gear member 18 will be in driving engagement with one of the output gear members 26 when the pin 22 is at one of the stop positions 16a. When the pin 22 is at one of the stop positions 16a, and the input shaft 12 is rotated in one direction, the drive gear member 18 will be rotated with the input and cam shafts 12 and 14 owing to the engagement of the pin 22 with the adjacent end portion of the cam groove 16. The drive gear member 18 thus will serve to rotatably drive the output gear member 26 with which it is in meshing engagement. If the input shaft 12 is then rotated in the opposite direction, the friction of the drag device 17 upon the gear member 18 will cause the pin 22 to move along the cam groove 16 toward the next stop position 16a. This will result in the axial movement of the drive gear member 18 along the cam shaft 14 into meshing engagement with the next succeeding output gear member 26 as the pin 22 reaches the next stop position 16a. Thereafter, alternate rotation of the input shaft 12 in opposite directions will continue this sequence of operation such that the drive gear member 18 will be sequentially moved into operative engagement with each of the output gear members 26 and will rotatably drive each of the output gear members sequentially in opposite directions.

In order to prevent the pin 22 from moving backwards in the cam groove 16, each of the cam groove portions may be recessed relative to the adjacent cam groove portion, in the manner shown in FIG. 3, such that when the pin 22 reaches a stop position 16a, it drops into the next cam groove portion and can not move backwards when the direction of the cam member 14 is reversed. Within the scope of this invention, there are many other well-known ways in which the pin 22 could be prevented from moving backwards in the cam groove 16, other than that specifically shown in FIG. 3. Some such alternate methods include using a guide at the end of pin 22 (not shown), or a lead for directing pin motion in each cam groove 16 (not shown).

Referring now to FIG. 4, a different cam groove configuration is illustrated for use with the control apparatus when it is desired to rotate each of the output members in both clockwise and counter-clockwise directions. The modified cam groove 116 formed in the cam shaft 14 connected to the input shaft 12 is provided with a plurality of pairs of stop positions 116a, each pair being disposed in a common plane that is substantially normal to the axis of the input shaft 12. In this manner, rotation of the input shaft 12 can effect movement of the pin 22 along the cam groove 116 between

the stop positions 116a disposed in the same plane that is normal to the input shaft axis. Such movement will not result in axial movement of the drive gear member 18 into engagement with the next succeeding output gear member 26, but instead will maintain the drive gear member 18 in engagement with the same output gear member 26 and will result in the drive member 18 and output gear member 26 being rotated in a direction opposite to that of the drive member 18 when the pin 22 was disposed in the previous stop position 116a in the same plane.

Thereafter, if the input shaft 12 is rotated in the opposite direction, the pin 22 will be moved along the cam groove 116 to the next stop position 116a which is disposed in a different plane that is normal to the input shaft axis. This latter movement of the pin 22 will cause the drive gear member 18 to move axially, owing to the friction of the drag device 17 and the rotation of the input shaft 12, along the exterior surface of the cam shaft 14 until it is in driving engagement with the next output gear member 26, which may then be rotatably driven by the gear member 18 in opposite directions, depending on the direction of rotation of the input shaft 12 and cam shaft 14.

The configuration of the cam grooves 16 and 116 shown in FIGS. 2 and 4, respectively, are merely examples of types of cam grooves that could be utilized for controlling output functions in accordance with the present invention. Within the scope of this invention, any suitable type of cam groove configuration could be utilized, depending on the timing and sequence of the output functions desired.

A modified form of the control apparatus 10 is shown in FIGS. 5, 6, and 7. The modified apparatus 200 comprises a rotatable input shaft 202 having a gear 204 keyed thereto for cooperating with a suitable output gearing arrangement (not shown) that is driven by a reversible drive means such as an electric motor (not shown). A plurality of annular cam members 206 are mounted in axially spaced relation on the input shaft 202 and are keyed thereto at 208 so as to be rotatable with the input shaft. Each of the cam members 206 is provided with a cam groove 210 in the outer surface thereof. The cam groove 210 of each annular member 206 may be of any suitable or desired configuration, and each cam groove may be the same as or different from the cam groove of one or more of the other cam members 206.

A drive or follower member 212 is slidably and rotatably mounted on the exterior surface of each of the annular cam members 206 and is provided with an inwardly extending pin 214 that is slidably disposed in the cam groove 210 of the adjacent cam member 206. The pin 214 is slidably mounted in a bore in the follower member 212 and is urged toward the cam groove 210 by a spring 215 disposed within the bore, as shown in FIG. 6. A plate member 217 serves to close the bore and is secured to the follower member 212 by a plurality of screws 219. In addition, in contact with the outer surface or other suitable surface of the follower member 212 is a drag device 213 of any suitable type. The drag device 213 supplies sufficient drag friction to the follower member 212 to cause translation rather than rotation of the follower member 212 along the annular cam member 206, until the pin 214 reaches the

end of the cam groove 210a. Upon reaching the end of cam groove 210a, the drag friction of the drag device 213 is overcome thus allowing rotation of the follower member 212. It is seen, therefore, that rotation of the input shaft 202 and the annular cam members 206 mounted thereon will result in rotation and/or axial movement of the follower members 212 with or along the cam members 206, owing to the positioning or movement of the pins 214 in the cam grooves 210 and the drag device 213. The direction of rotation and axial movement of each of the follower members 212 will be determined by the configuration of each of the cam grooves 210.

Each of the follower members 212 is provided with a plurality of second pins 216 extending outwardly from one side thereof, and a plurality of third pins 218 extending outwardly from the other side thereof. Each of the pins 216, 218 is biased laterally outwardly by a helical spring 220 in surrounding relation thereto. A pair of output members in the form of gear members 222 of any suitable type are rotatably mounted on the input shaft 202 on opposite sides of each annular cam member 206. Each of the gear members 222 is provided with a plurality of apertures 224 therein which are adapted to slidably receive the pins 216 and 218 of the adjacent follower member 212. Within the scope of the present invention, the gear members 222 may be of any suitable construction and may each be the same as or different from the other gear members 222.

In the operation of the modified control apparatus 200, when the rotation of the input shaft 202, the annular cam members 206 and the drag device 213 effects the axial movement of one or more of the follower members 212, the pins 216 or 218 on the follower members 212 are moved into the apertures 224 of the adjacent gear member 222 so as to drivingly connect the follower member 212 and adjacent gear member for joint rotatable movement with the input shaft 202. Thereafter, a predetermined rotation of the input shaft 202 can effect rotation of the follower member 212 and the connected gear member 222, owing to the position of the respective pin 214 in the respective cam groove 210. The operation of the modified control apparatus 200, therefore, is very similar to the operation of the control apparatus 10 shown in FIG. 1.

With the modified control apparatus 200 shown in FIGS. 5 through 7, any desired number of cam members 206, follower members 212 and gear members 222 may be provided on the input shaft 202, so that a very large number of output functions can be effected by the sequential rotation of the input shaft 202 in the same or opposite directions.

I claim

1. In control apparatus wherein a drive member is movable into driving engagement with each of a plurality of driven output members for effecting a plurality of output functions, the improvement comprising:

a movable input member having a cam groove disposed on the outer surface thereof, and follower means mounted on said drive member and slidably engaged in said cam groove, whereby predetermined movement of said input member causes said follower means to move along said cam groove and to effect movement of said drive member into driving engagement with one of said output members.

2. The apparatus of claim 1 wherein said input member is a rotatable shaft and said follower means is a pin.

3. The apparatus of claim 2 wherein said drive member is an annular member that is mounted on said input shaft for rotation and axial movement relative thereto, and said pin is mounted on the interior annular surface of said drive member.

4. The apparatus of claim 3 wherein said output members are gear members, and said drive member is a gear member that is adapted to mesh with each of said output members.

5. The apparatus of claim 3 wherein said output members comprise a pair of gear members, and said drive member is a follower member that is disposed between said output members and is axially movable along said input shaft into driving engagement with one of the other of said output members.

6. The apparatus of claim 1 further comprising drag means in engagement with said follower means to cause movement of said follower means along said cam groove.

7. In control apparatus wherein a drive member is movable into driving engagement with each of a plurality of rotatable output members for effecting a plurality of output functions, the improvement comprising:

a rotatable input shaft having an axially extending cam groove disposed on the outer surface thereof, said drive member being mounted on said input shaft for rotation and axial movement relative thereto, and

a pin mounted on said drive member and being slidably disposed in said cam groove, whereby rotation of said input shaft in one direction causes said pin to move along said cam groove in a

first direction and effects movement of said member into driving engagement with one of said output members.

8. The apparatus of claim 7 wherein said pin is mounted on the interior surface of said drive member.

9. The apparatus of claim 7 wherein said drive member has a bore therein and said pin is slidably mounted in said bore, and wherein spring means is disposed in said bore for urging said pin into engagement with said cam groove.

10. The apparatus of claim 7 wherein said cam groove is so constructed that rotation of said input shaft in the other direction causes said pin and said drive member to rotate with said input shaft.

11. The apparatus of claim 7 wherein said cam groove is formed with a plurality of recessed portions into which said pin drops to prevent movement of said pin along said cam groove in a direction opposite to said first direction each time said input shaft is rotated.

12. The apparatus of claim 7 wherein said cam groove is formed in the outer surface of an annular cam member mounted on the outer surface of said input shaft.

13. The apparatus of claim 12 wherein said drive member is annular and is rotatably and slidably mounted on the outer surface of said cam member.

14. The apparatus of claim 7 wherein a plurality of drive members are mounted on said input shaft for driving engagement with different output members.

15. The apparatus of claim 7 wherein said drive member and said output members are rotatable gear members.

16. The apparatus of claim 7 further comprising drag means in engagement with said follower means to cause movement of said follower means along said cam groove.
